US00D738898S

(12) **United States Design Patent**
Herold et al.

(10) **Patent No.:** **US D738,898 S**
(45) **Date of Patent:** **** Sep. 15, 2015**

(54) **DISPLAY SCREEN WITH GRAPHICAL USER INTERFACE**

(71) Applicant: **Microsoft Corporation**, Redmond, WA (US)

(72) Inventors: **Jeffrey Alan Herold**, Kirkland, WA (US); **Nicholas R. Barling**, Redmond, WA (US); **Charla Pereira**, Seattle, WA (US); **Arianne Taylor**, Woodinville, WA (US)

(73) Assignee: **Microsoft Corporation**, Redmond, WA (US)

(**) Term: **14 Years**

(21) Appl. No.: **29/478,846**

(22) Filed: **Jan. 9, 2014**

(51) LOC (10) Cl. **14-04**

(52) U.S. Cl.
